UNITED STATES PATENT OFFICE.

FREDRICK HOFFMANN, OF LOUISVILLE, KENTUCKY.

MATTRESS.

No. 893,732.

Specification of Letters Patent.

Patented July 21, 1908.

Application filed October 31, 1907. Serial No. 400,052.

To all whom it may concern:

Be it known that I, FREDRICK HOFFMANN, a citizen of the United States, residing at Louisville, in the county of Jefferson and State of Kentucky, have invented a new and useful Improvement in Mattresses, of which the following is a specification.

This invention is an improved form of mattress, the object being to provide a mattress of such construction that the filling thereof will not become thin or compressed at certain points and thick or bulging at other points, and another object is to provide a mattress of such construction that access to the interior thereof can be quickly and easily had.

My invention consists in the novel features of construction, combination and arrangement of parts, hereinafter fully described and pointed out in the claims.

In the drawing forming a part of this specification:—Figure 1 is a longitudinal sectional view of the mattress. Fig. 2 is a longitudinal sectional view of the mattress. Fig. 3 is a transverse sectional view. Fig. 4 is a detail perspective view of the clamp. Fig. 5 is a detail sectional view illustrating the operation of the clamp.

Referring to the drawings A indicates the ticking or casing, which is constructed substantially the same as usual except that at one end the ticking is divided longitudinally as shown at A', and the edges are turned around and sewed over wire rods B, and the slit in the side of the ticking is closed by

means of a series of spring metal clips C, which is adapted to engage the beaded edges of said strip as most clearly shown in Figs. 1, 3 and 5. The ticking or casing A is divided longitudinally into a series of compartments, by means of a series of fabric partitions D and each compartment is separately filled or stuffed with stuffing E which may be of hair, cotton or any other suitable material.

By having the mattress open at one end, it is obvious that if the mattress becomes packed at any particular point, the stuffing in one or more of the compartments may be quickly and easily removed, loosened up and replaced, thereby restoring the mattress to its original and proper form.

It will thus be seen that I provide an exceedingly cheap, simple and efficient construction of mattress which can be quickly and easily renovated whenever desired.

Having thus fully described my invention, what I claim as new and desire to secure by Letters Patent is:—

A mattress opened at one end, and having the meeting edges of said opened side stiffened by means of wire rods, spring clips for engaging the said edges for the purpose of holding them together, the casing being divided into a series of compartments and the stuffing in the said compartments all arranged substantially as described.

FREDRICK HOFFMANN.
